US00D716183S

(12) **United States Design Patent**
Crooks

(10) **Patent No.:** **US D716,183 S**
(45) **Date of Patent:** **** Oct. 28, 2014**

(54) **DEVICE FOR SECURING AN ARTICLE OF CLOTHING**

(71) Applicant: **Jenell Boley Crooks**, Lee's Summit, MO (US)

(72) Inventor: **Jenell Boley Crooks**, Lee's Summit, MO (US)

(73) Assignee: **4JC's Development, LLC**, Lake Lotawana, MO (US)

(**) Term: **14 Years**

(21) Appl. No.: **29/448,027**

(22) Filed: **Mar. 8, 2013**

(51) LOC (10) Cl. **02-07**

(52) U.S. Cl.

USPC **D11/215**

(58) **Field of Classification Search**

(57) **CLAIM**

The ornamental design for a device for securing an article of clothing, as shown and described.

DESCRIPTION

FIG. 1 is a perspective view of one embodiment of the present invention.

FIG. 2 is a front elevation view of one embodiment of the present invention.

FIG. 3 is a rear elevation view of one embodiment of the present invention.

FIG. 4 is a left elevation view of one embodiment of the present invention.

FIG. 5 is a right elevation view of one embodiment of the present invention.

FIG. 6 is an alternative perspective view of one embodiment of the present invention.

FIG. 7 is a top plan view of the present invention.

FIG. 8 is a bottom plan view of the present invention.

FIG. 9 is a perspective view of a second embodiment of the present invention.

FIG. 10 is a front elevation view of a second embodiment of the present invention.

FIG. 11 is a rear elevation view of a second embodiment of the present invention.

FIG. 12 is a left elevation view of a second embodiment of the present invention.

FIG. 13 is a right elevation view of a second embodiment of the present invention; and,

FIG. 14 is an alternative perspective view of a second embodiment of the present invention.
